UNITED STATES PATENT OFFICE.

EDWARD BRICK, OF LOWELL, MASSACHUSETTS, ASSIGNOR OF TWO-THIRDS
TO EDWARD W. THOMAS AND ORANGE H. STAFFORD, BOTH OF SAME
PLACE.

PICKER-STAFF CHECK FOR LOOMS.

SPECIFICATION forming part of Letters Patent No. 416,665, dated December 3, 1889.

Application filed May 7, 1888. Serial No. 273,159. (No model.)

To all whom it may concern:

Be it known that I, EDWARD BRICK, a citizen of the United States, residing at Lowell, in the county of Middlesex and Commonwealth of Massachusetts, have invented a certain new and useful Improvement in Picker-Staff Checks for Looms, of which the following is a specification.

My invention relates to picker-staff checks; and it consists in the devices and combinations hereinafter described and claimed.

In the accompanying drawings, Figure 1 is an isometric view of a part of a lay-beam provided with the picker-staff, slot of the picker-staff, a part of the lay-staff, the Stearns parallel motion, and my improvement; Fig. 2, a front elevation of the lower part of the picker-staff and of the other parts shown in the lower part of Fig. 1, the picker-staff being represented as moved outward; Fig. 3, an elevation of the inner side of the part shown in Fig. 2; Fig. 4, an isometric view of the outer portion of the check-rod, buffer-arm, and buffer; Fig. 5, an isometric view of the outer portion of the check-rod and buffer-arm, omitting the buffer; Fig. 6, an isometric view of the rear portion of the buffer-arm; Fig. 7, an isometric view of the buffer detached and flat; Fig. 8, a similar view of the buffer, except that its end portions are represented as bent into the positions they occupy when attached to the buffer-arm. Figs. 9 and 10 are vertical transverse sections of the buffer and buffer-arm on the lines $x-x$ and $y-y$, respectively, in Fig. 4.

The lay-shaft A, rocker-bed a, rocker a', roll a'', and strap a''' of the "Stearns parallel motion," above referred to, the picker-staff P, and the lay-beam A', provided with the picker-staff slot a'', are all of the usual construction and operation.

To the rocker-bed a, I attach a bracket B, either by casting the same in one piece with said rocker-bed in the case of new work, as shown in Figs. 2 and 3, or by means of a clamp b, with which the lower end of said bracket may be provided, as shown in Fig. 1, where the lower part of said bracket is formed in two parts, one of which b' is a removable

piece secured by a bolt b² to the main part 50 of said bracket, the lower part of the body of the bracket and the piece b grasping opposite sides of a hanger a⁵, which supports the shaft a⁶, on which the strap-roll a² turns. The upper part of the bracket B is provided 55 with vertical ears b³b⁴, through holes in which slides the check-rod C. The check-rod is arranged parallel with the lay-shaft A, and is provided with a backwardly-extending buffer-arm c, having a convex or semi-cylindrical 60 inner face arranged outside of the picker-staff. A spiral spring D surrounds the check-rod between the ears b³b⁴, and is compressed between the outer ear b⁴ and an adjustable collar c', secured on said check-rod by a set-screw c², 65 which turns in said collar and thrusts against said rod. The compression of the spring D may be varied by the adjustment of the collar c' on the check-rod. Another collar c³, adjustable by means of a set-screw c⁴ turning in said last-named collar against said check-rod, limits the inward motion of the check-rod by striking against the ear b³. The 70 picker-staff when moved outward strikes against the buffer-arm c, moving the check-rod outward and compressing the spring D, and thereby diminishing the shock of the picker-staff and gradually stopping the same. To diminish the shock of the picker-staff against the buffer-arm still further and to 75 diminish the wear of these parts and the noise occasioned by their meeting, I provide the buffer-arm with a buffer E, of the form shown in Fig. 7, the same being a piece of leather or other similar sheet material cut in the 80 form shown—that is to say, provided with a dovetail e at each end, these dovetails being inserted in vertical slots c⁵ in the buffer-arm, these slots being connected by another slot c⁶, into which the dovetails are first inserted and 85 along which they are moved into the slot c⁵, being then twisted into place, so that the buffer when in position is of the shape shown in Fig. 4.

The position of the picker-staff check on 90 the rocker-bed enables a very strong and durable spring to be used, as when there placed the compression of the spring is very

slight in amount and the leverage of the shuttle on the picker-stick is very great, whereas if the check were arranged on the lay-beam the spring, if strong enough to act as a check, would offer so much and such sudden resistance to the shuttle as to cause the filling to be knocked off—that is, would cause the cop to be broken—and if the resistance of the spring were reduced sufficiently to avoid the knocking off of the filling the device would not be effectual as a check, and the shuttle would need to be checked and prevented from bounding out of the shuttle-box by tightening up the binder-spring, which would make it more difficult for the shuttle to leave the box as well as to enter it and require more power to throw the shuttle. The position of the spring so near the fulcrum of the picker-staff and the slight amount of compression thereof required makes the wear of the spring very slight, and the slight projection of the device beyond the picker-staff, which is merely the thickness of the arm *c*, is not sufficient to expose the device to injury from passing trucks, such as are commonly used in cotton-factories and which would frequently strike the device if it projected beyond the rocker-bed.

I claim as my invention—

- 3c 1. The picker-staff check herein described, consisting of the combination of the rocker-bed provided with a bracket, cast or rigidly secured thereon, and having ears, the check-rod sliding in said ears, and provided at its outer end, outside of said ears, with a laterally-extending arm arranged at about right angles to said rod, and a spring surrounding said rod and compressed between a collar with which said rod is provided and one of said ears, as and for the purpose specified.
2. The combination of the rocker-bed, a bracket cast or rigidly secured thereon and having ears, the check-rod sliding in said ears and provided at its outer end, outside of said ears, with a laterally-extending arm arranged at about right angles to said rod, a buffer, of leather or other suitable material, secured to said arm, and a spring surrounding said rod

and compressed between a collar with which said rod is provided and one of said ears, as and for the purpose specified.

3. The combination of the rocker-bed, the bracket secured to the rocker-bed and having ears, the check-rod sliding in said ears and provided with an arm arranged at about right angles to said rod, and having vertical slots, and a horizontal slot connecting said vertical slots, a buffer, of leather or other suitable sheet material, having dovetail ends, adapted to be placed in said horizontal slot and to be moved therefrom into said vertical slots and to be retained therein, and a spring surrounding said rod and compressed between a collar with which said rod is provided and one of said ears, as and for the purpose specified.

4. The combination of the bracket adapted to be secured to the rocker-bed and having ears, the check-rod sliding in said ears and provided with an arm arranged at about right angles to said rod, and provided with a buffer, a spring surrounding said rod, and a collar, adjustable on said rod, to compress said spring between said collar and one of said ears, to vary the compression of said spring, as and for the purpose specified.

5. The combination of the bracket adapted to be secured to the rocker-bed and having ears, the check-rod sliding in said ears and provided with an arm arranged at about right angles to said rod, a spring surrounding said rod and compressed between a collar with which said rod is provided and one of said ears, and another collar arranged on said check-rod and adjustable thereon between said first-named collar and the other one of said ears, to limit the return motion of said rod and to vary the amount of said motion, as and for the purpose specified.

In witness whereof I have signed this specification, in the presence of two attesting witnesses, this 1st day of May, 1888.

EDWARD BRICK.
